UNITED STATES PATENT OFFICE

WILLIAM O. WORTH, OF CHICAGO, ILLINOIS.

DESIGN FOR A FRAME FOR MOTOR-VEHICLES.

SPECIFICATION forming part of Design No. 31,867, dated November 21, 1899.

Application filed September 9, 1899. Serial No. 730,028. Term of patent 14 years.

To all whom it may concern:

Be it known that I, WILLIAM O. WORTH, a citizen of the United States, residing at Chicago, in the county of Cook and State of Illinois, have invented and produced a new and original Design for Frames for Motor-Vehicles, of which the following is a specification, reference being had to the accompanying drawings, forming part hereof.

10 Figure 1 is a plan view of a motor-supporting frame, showing my new design. Fig. 2 is a section through line 2.

The same letters refer to like parts in both views.

15 A structure A of the frame is composed of one piece of channel-iron bent into the form shown, so that the channel therein faces inwardly. Near the center of the structure A, joining the two sides thereof, is a cross-piece 20 D', bent as shown in Fig. 2, with the channel therein facing outwardly. A similar cross-piece D, bent as shown in Fig. 2, also having the channel portion thereof facing outwardly, joins the two sides of the structure A at a 25 point where the structure begins to narrow. The two ends of the structure A are joined together by the cross-piece B. The pieces C C' are flat plates that are joined to the bot-

tom of the pieces A and B at the junction of these parts.

The essential features of my design therefore embrace the substantially rectangular round-cornered contracted front structure formed of channel-iron, with the channel thereof facing inwardly, a downwardly-curved 35 channel-iron cross-piece joining the two sides of the structure near the center thereof, another similar channel-iron cross-piece parallel therewith joining the two sides of the main structure at a point where the two sides 40 thereof curve toward each other, and a cross-piece joining the ends of the structure forming a square-shaped end therewith, and a flat plate extending inwardly at the bottom of each square corner formed by the main structure and the said cross-piece.

Having described my invention, what I claim, and desire to secure by Letters Patent of the United States, is—

The design for a frame for motor-vehicles, 50 as herein shown and described.

WILLIAM O. WORTH.
